Primary Examiner — Patricia A Palasik(57) **CLAIM**

The ornamental design for a gear, as shown and described.

DESCRIPTION

FIG. 1 is a perspective view of a gear showing my new design;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

The broken lines in the figures are to show portions of the gear and form no part of the claimed design.
